JOHN FRANCIS BRICE, OF BENSELEM, PENNSYLVANIA.

INTERNAL-COMBUSTION ENGINE.

1,149,179.

Specification of Letters Patent. Patented Aug. 10, 1915.

Application filed May 6, 1914. Serial No. 836,654.

To all whom it may concern:

Be it known that I, JOHN FRANCIS BRICE, a citizen of the United States, and a resident of Bensalem, in the county of Bucks and State of Pennsylvania, have invented a new and Improved Internal-Combustion Engine, of which the following is a full, clear, and exact description.

The invention relates to internal combustion engines of the two-cycle type, in which the explosive charge is compressed in the crank case and such, for instance, as is shown in the application for Letters Patent of the United States, No. 782,657, filed by me on August 2, 1913.

The object of the present invention is to provide certain new and useful improvements in this type of internal combustion engine whereby regularity of operation throughout a wide range of speeds and under all variations of the throttle is obtained and the working chamber is completely scavenged of the products of combustion once in each revolution.

In order to accomplish the desired result, use is made of a piston having an extension slidingly engaging an extension of the cylinder, inlet ports near one end of the working chamber, exhaust ports adapted to be uncovered by the piston near the other end of the working chamber at the time the chamber reaches its greatest extent, transfer ports adapted to be in register with the inlet ports near the end of the working stroke after the exhaust ports are partly open, a transfer passage from the crank case to the transfer ports, means for admitting an explosive charge to the crank case during a part of the return stroke of the piston, and air supply ports adapted to admit atmospheric air to the transfer ports near the end of the return stroke of the piston and after the admission of the explosive charge to the crank case has already begun.

A practical embodiment of the invention is represented in the accompanying drawings forming a part of this specification, in which similar characters of reference indicate corresponding parts in all the views.

Figure 1 is a central cross section of the internal combustion engine with the piston in uppermost position; Fig. 2 is a similar view of the same with the piston in lowermost position; Fig. 3 is a like view of the same with the piston in position immediately after it uncovers the admission ports

and prior to opening the air supply ports; Fig. 4 is a central cross section of a modified form of the internal combustion engine with the piston in uppermost position; Fig. 5 is a similar view of the same with the piston in lowermost position; and Fig. 6 is a cross section of the same with the piston in position immediately after it uncovers the admission ports and prior to opening the air supply ports.

In the internal combustion engine shown in Figs. 1, 2 and 3, the cylinder A has its lower end A' opening into the closed crank case B and the upper end A² of the said cylinder A is provided with a head C forming with the wall of the upper end A² of the cylinder A an exhaust chamber D having an outlet D' for conducting the products of combustion to a suitable place of discharge. The bottom of the head C carries an ignition device E of any approved construction.

In the cylinder A reciprocates a piston F connected by a pitman G with a crank H on the main engine shaft I extending through the crank case B. The piston F is H-shaped in section and consists of a horizontal partition or abutment F' and an upper cylindrical portion F² and a lower cylindrical portion F³, the upper portion F² extending into the annular exhaust chamber D and being open at its upper end, the head C extending into the said upper portion F², thus forming a working chamber F⁴ in the upper portion F² of the piston F. The lower end of the lower portion F³ of the piston F is open and opens into the lower portion A' of the cylinder A and is thus open to the crank case.

Into the lower end A' of the cylinder A open a series of annularly arranged admission ports a located a distance from the bottom edge of the cylinder and at such a point that when the piston F is in its uppermost position, as shown in Fig. 1, the said ports a are uncovered. The admission ports a lead from an annular chest J formed in the wall of the cylinder A and connected by a pipe J' with a suitable source of explosive charge supply, it being understood that the said admission ports a are normally closed by the piston F and are uncovered by the latter at the time the piston F approaches uppermost position, as shown in Fig. 3, so that the explosive charge can pass by way of the admission ports a into the lower end A'.

of the cylinder A to pass from the latter into the crank case B to be compressed therein during the next downward movement of the piston F.

5 The upper end of the upper portion F² of the piston F is provided with a series of annularly arranged exhaust ports b adapted to connect the interior of the working chamber F⁴ with the exhaust chamber D at the 10 time the piston F moves into lowermost position, as shown in Fig. 2. The lower end of the upper portion F² of the piston F is provided with a series of annularly arranged inlet ports c located directly above 15 the abutment F', and the said inlet ports c are adapted to register with a series of transfer ports d at the time the piston F moves into lowermost position and after the exhaust ports are already partly open, as 20 shown in Fig. 2. The transfer ports d are arranged annularly in the cylinder wall and connect with transfer passages K connected with the crank case. The lower portion F³ of the piston F² is provided exteriorly with 25 an annular recess or depression L adapted to connect the transfer ports d with a series of air supply ports e at the time the piston F moves into uppermost position (see Fig. 1) and after the admission ports are already 30 partly open (see Fig. 3). The air supply ports e are arranged in the wall of the cylinder A immediately below the transfer ports d and lead from an annular chamber N connected by a pipe N' with the atmos- 35 phere.

The operation is as follows: When the engine is running and the piston F nears its uppermost position, as shown in Fig. 3, then the ports a are uncovered by the piston F to allow an explosive charge to pass into the lower end A' of the cylinder A and into the crank case B, and after the ports a are uncovered the annular recess L connects the fresh air supply ports e with 45 the transfer ports d to allow fresh atmospheric air to pass by way of the said ports e, recess L and transfer ports d into the transfer passages K. During the following down stroke of the piston F the transfer ports d 50 and the air supply ports e are disconnected and the admission ports a are closed so that the explosive charge in the crank case B and the fresh air in the transfer passages K are compressed. When the piston F approaches 55 its lowermost position the exhaust ports b connect the working chamber F⁴ with the exhaust chamber D to allow the products of combustion from a previous explosion to escape into the said exhaust chamber D and 60 from the latter by way of the outlet D' to a suitable place of discharge. This outward movement of the products of combustion is assisted and carried to completion by the subsequent registration of the ports d and c, 65 allowing the air compressed in the transfer

passages K to pass by way of the ports d and c into the working chamber F⁴, the air being followed in turn by the new charge of explosive mixture. It will be noticed that this inrushing compressed air tends to scour the working chamber F⁴ of the products of combustion from the previous explosion and this air also prevents the now following new charge from mixing with the outgoing products of combustion. During the following return or upward stroke of the piston F, the ports c, d are disconnected and likewise the exhaust ports b are disconnected from the interior of the working chamber F⁴ so that the explosive charge contained in the working chamber F⁴ is compressed during the upward stroke of the piston F. The explosive charge is retained within the working chamber F⁴ at the time the piston F reaches an uppermost position and then the charge is ignited by the igniting device E to give impulse to the piston F on the down stroke. It is understood that when the piston F moves into uppermost position, the admission ports a are uncovered to allow 90 recharging of the crank case B with another explosive charge, and the transfer passages K are subsequently charged with fresh air by way of the ports e and d and the depression L. By this arrangement a double purpose is accomplished, namely, first, drawing into the crank case a charge of the explosive mixture while the piston is still under a forceful suction action and irrespective of the position of the throttle, and, 95 second, admitting air into the upper end of the transfer passage subsequent to the beginning of the admission of the explosive charge into the crank case, to make up for the deficiency in the volume of the explosive mixture supplied to the crank case and to locate the atmospheric air in the upper portion of the transfer passage for the air to pass into the working chamber of the cylinder ahead of the explosive mixture for 100 scouring purposes on the next downward stroke of the piston.

From the foregoing it will be seen that no matter how little the throttle is open the suction in the crank case begins to draw in the explosive mixture prior to admitting air into the transfer passage and the amount of air subsequently supplied makes up for the deficiency in volume of explosive mixture supplied during the suction stroke of 115 the piston, and the new charge is always at the same transfer pressure at the time of the beginning of its delivery into the working chamber.

By the arrangement described a very desirable flexibility is obtained whereby the engine can be throttled to any desired degree without any progressive diminution in the amount of explosive mixture at each stroke.

It will be seen that as the engine's speed diminishes in response to partial closing of the throttle, the length of each time interval, wherein the suction acts only to effect an intake of explosive mixture before the air admission begins, increases progressively, and consequently the amount of explosive mixture admitted at each stroke increases progressively until the force exerted at each stroke is sufficient to maintain a uniform engine speed and hence the engine is not liable to come to a standstill.

It is further understood that by the arrangement described atmospheric air is compressed and passed unmixed into the working chamber for scouring purposes ahead of the charge of the explosive mixture, and in order to successfully obtain the result it is imperative that the atmospheric air does not reach the crank case but is confined within the transfer passage.

It will be noticed that by providing annularly arranged inlet ports *c* and transfer ports *d* a very large port area is obtained to insure a complete filling of the working chamber *F*⁴ with a new charge, and by providing the annularly arranged exhaust ports *b* a large exhaust area is obtained to insure the complete escape of the products of combustion at the time the piston moves into lowermost position (see Fig. 2). It will also be noticed that a higher speed may be obtained by providing inlet and exhaust ports extending substantially around the entire circumference at opposite ends of the working chamber, the paths of incoming and outgoing gases are shortened and straightened and area of contact between the two is reduced. It will further be noticed that the diameter of the working chamber *F*⁴ is less than the diameter of the piston *F* and hence the fluid displacement in the crank case *B* is greater than that in the working chamber *F*⁴, and this difference in volume is utilized to effect a complete scouring of the working chamber *F*⁴ of its products of combustion.

In the modified form shown in Figs. 4, 5 and 6, the lower end of the cylinder *A*⁴ opens into the closed crank case *B*' and the upper end of the said cylinder *A*⁴ is provided with a reduced cylindrical extension *A*⁵, the lower end of which extends a short distance into the upper end of the cylinder *A*⁴. The upper portion of the cylinder *A*⁴ forms the working chamber *A*' and is provided with an ignition device *E*', of any approved construction. In the cylinder *A*⁴ reciprocates a piston *F*⁵ provided at its upper end with a reduced hollow extension *F*⁶ closed at the top and opening at its lower end into the hollow piston *F*⁵. The piston *F*⁵ is connected by a pitman *G*' with a crank *H*' on the main engine shaft *I*' extending through the crank case *B*'.

65 Into the lower portion of the cylinder *A*⁴

open a series of annularly arranged admission ports *a*' located a distance from the bottom edge of the cylinder *A*⁴ and at such a point that when the piston *F*⁵ is in its uppermost position, as shown in Fig. 4, the said ports *a*' are uncovered. The admission ports *a*' lead from an annular chest *J*² formed in the wall of the cylinder *A*⁴ and connected by a pipe *J*³ with a suitable source of explosive charge supply, it being understood that the said admission ports *a*' are normally closed by the piston *F*⁵ and are uncovered by the latter at the time the piston *F*⁵ approaches uppermost position, as shown in Fig. 6, so that the explosive charge can pass by way of the admission ports *a*' into the lower end of the cylinder *A*⁴ to pass from the latter into the crank case *B*' to be compressed therein during the next downward movement of the piston *F*⁵. The wall of the cylinder *A*⁴ is provided at the lower end of its working chamber *A*' with a series of annularly arranged exhaust ports *b*' leading to an exhaust chamber *D*² from which extends an exhaust pipe *D*³ for carrying off the products of combustion to a desired place of discharge. The exhaust ports *b*' are adapted to connect the interior of the working chamber *A*' with the exhaust chamber *D*² at the time the piston *F*⁵ moves into lowermost position, as shown in Fig. 5. The lower end *A*⁶ of the cylindrical extension *A*⁵ is provided with a series of annularly arranged inlet ports *c*' opening into the upper end of the working chamber *A*'.

The upper end of the piston extension *F*⁶ is provided with a series of annularly arranged transfer ports *d*', and the upper end of the cylinder extension *A*⁵ is provided with a series of annularly arranged air supply ports *e*'. The transfer ports *d*' register with the air supply ports *e*' at the time the piston *F*⁵ and its extension *F*⁶ are in uppermost position, as shown in Fig. 4, and the said transfer ports *d*' register with the inlet ports *c*' at the time the piston *F*⁵ and its extension *F*⁶ move into lowermost position, as shown in Fig. 5.

By reference to Fig. 6 it will be noticed that when the piston *F*⁵ and its extension *F*⁶ is on the upward stroke the admission ports *a*' are uncovered by the piston *F*⁵ prior to the ports *d*' registering with the air supply ports *e*'.

The operation is as follows: When the engine is running and the piston *F*⁵ and its extension *F*⁶ nears its uppermost position, as shown in Fig. 6, then the ports *a*' are uncovered by the piston *F*⁵ to allow an explosive charge to pass into the lower end of the cylinder *A*⁴ and into the crank case *B*', and after the ports *a*' are uncovered the ports *d*' connect with the air supply ports *e*' to allow fresh atmospheric air to pass by way of the said ports *e*' and *d*' into the upper end of the extension *F*⁶.

of the piston F^5 . During the following down stroke of the piston F^5 and its extension F^6 the transfer ports d' and the air supply ports e' are disconnected and the admission ports a' are closed so that the explosive charge in the crank case B' and the fresh air in the upper portion of the piston extension F^6 are compressed. When the piston F^5 and its extension F^6 approach 10 lowermost position then the exhaust ports b' connect the working chamber A^7 with the exhaust chamber D^2 to allow the products of combustion from a previous explosion to escape into the said exhaust chamber D^2 and 15 from the latter by way of the exhaust pipe D^3 to a place of discharge. This outward movement of the products of combustion is assisted and carried to completion by the subsequent registration of the ports d' and 20 e' , allowing air compressed in the upper end of the piston extension F^6 to pass by way of the ports d' and e' into the working chamber A^7 , the air being followed in turn by the new charge of explosive mixture coming up 25 from the crank case B' by way of the piston F^5 and its extension F^6 . It will be noticed that this inrushing compressed air tends to scour the working chamber A^7 and this air also prevents the now following new charge 30 from mixing with the outgoing products of combustion. During the following return or upward stroke of the piston F^5 and its extension F^6 the ports d' and e' are disconnected and likewise the exhaust ports b' are 35 closed so that the explosive charge contained in the working chamber A^7 is compressed during the upward stroke of the piston F^5 and its extension F^6 . The explosive charge is retained within the working chamber A^7 40 at the time the piston F^5 and its extension F^6 reach an uppermost position, and then the charge is ignited by the igniting device E' to give impulse to the piston F^5 on the down stroke. It is understood that when 45 the piston F^5 and its extension F^6 moves into uppermost position the admission ports a' are uncovered to allow recharging of the crank case B' with another explosive charge, and the upper end of the extension F^6 is 50 subsequently charged with fresh air by way of the ports d' and e' .

The advantages of this form of engine are the same as above described in reference to the engine shown in Figs. 1, 2 and 3, so that 55 further description is not deemed necessary.

It is understood that in the construction disclosed in Figs. 4, 5 and 6, the hollow piston F^5 and its extension F^6 form the transfer passage for conducting the new 60 explosive charge from the crank case B' into the working chamber A^7 .

Having thus described my invention I claim as new and desire to secure by Letters Patent:

65 1. In an internal combustion engine of

the two-cycle type, the combination of a cylinder having an extension at one end, a crank case connected with the other end of the said cylinder, a transfer passage connected with the crank case, a piston reciprocating in the said cylinder and slidably engaging the said cylinder extension, a working chamber, means for admitting an explosive charge to the said crank case at the time the piston nears the end of its return stroke, means for admitting air to the transfer passage after the said means for admitting the explosive charge is open, the said air admitting means and the said explosive charge admitting means remaining open concurrently and closing in reverse order, means for admitting the said air in the transfer passage to the working chamber ahead of the explosive charge, and means for exhausting the products of combustion from the working chamber ahead of the admission of the air. 70 75 80

2. In an internal combustion engine of the two-cycle type, the combination of a cylinder having an extension, a crank case, a working chamber, a piston reciprocating in the cylinder and having an extension slidable in the cylinder extension, inlet ports near one end of the working chamber, exhaust ports near the other end of the working chamber and adapted to be uncovered when the said chamber approaches its greatest extent, transfer ports adapted to be in register with the inlet ports at the time the piston nears the end of its working stroke and after the exhaust ports are already partly open, a transfer passage from the crank case to the said transfer ports, means for admitting an explosive charge to the crank case during the return stroke of the piston, and air supply ports adapted to admit atmospheric air to the transfer ports after the means for admitting the explosive charge to the crank case is already partly open, the said air supply ports and the said explosive charge admitting means remaining open concurrently and closing in reverse order. 90 95 100 105 110

3. In an internal combustion engine of the two-cycle type, the combination of a cylinder having an extension at one end, a crank case connected with the other end of the said cylinder, a transfer passage connected with the said crank case, a working chamber, a piston reciprocating in the said cylinder and having an extension slidably engaging the said cylinder extension, substantially annularly arranged admission ports for admitting an explosive charge to the crank case and adapted to be uncovered by the piston at the time the piston nears the end of the return stroke, substantially annularly arranged air supply ports for admitting air to the transfer passage and opened by the said piston after the latter 115 120 125 130

has uncovered the said admission ports, the latter and the said air supply ports remaining open concurrently and closing in reverse order, substantially annularly arranged 5 inlet ports controlled by the said piston for connecting the transfer passage with the working chamber at the time the piston nears the end of its working stroke to allow the air to pass into the 10 working chamber ahead of the explosive charge, and substantially annularly arranged exhaust ports leading from the working chamber and controlled by the piston and opened ahead of the admission of air 15 to the working chamber.

4. In an internal combustion engine of the two-cycle type, the combination of a cylinder provided at one end with an extension closed by a reentrant cylinder head, 20 a crank case connected with the other end of the said cylinder, a piston reciprocating in the said cylinder and provided at one end with an extension slidably engaging the said cylinder extension, the said piston extension forming a working chamber with the 25 said cylinder head and the said piston having an annular depression in its outer surface, substantially annularly arranged admission ports in the cylinder wall and

adapted to be uncovered by the piston at 30 the time the latter nears the end of its return stroke to admit an explosive charge to the crank case, symmetrically arranged transfer passages leading from the said crank case and terminating in substantially 35 annularly arranged transfer ports in the cylinder wall, substantially annularly arranged air supply ports in the cylinder wall and adapted to be connected by the said piston depression with the said transfer 40 ports to admit air to the transfer passage after the said admission ports for the explosive charge are open, substantially annularly arranged exhaust ports at the outer end of the said piston extension and adapted to be opened at the time the piston nears 45 the end of its power stroke, and substantially annularly arranged inlet ports at the inner end of the said piston extension and adapted to connect with the said transfer ports after the exhaust ports are open.

In testimony whereof I have signed my name to this specification in the presence of two subscribing witnesses.

JOHN FRANCIS BRICE.
